[57] CLAIM

The ornamental design for a wood putter head, as shown and described.

DESCRIPTION

FIG. 1 is a perspective view of a wood putter head showing my design;

FIG. 2 is a front view thereof;

FIG. 3 is a rear view thereof;

FIG. 4 is a right side view thereof, which is a mirror image of the left side thereof;

FIG. 5 is a top view thereof; and,

FIG. 6 is a bottom view thereof.

The broken line showing of a fragment shaft is for illustrative purposes only and forms no part of the claimed design.
